Primary Examiner — Elizabeth A. Albert(74) *Attorney, Agent, or Firm* — Birch, Stewart, Kolasch & Birch, LLP(57) **CLAIM**

The ornamental design for a shelf cover for plant cultivator, as shown and described.

DESCRIPTION

FIG. 1 is a top perspective view of a shelf cover for plant cultivator showing our new design;

FIG. 2 is a front view thereof where the rear view is a mirror image;

FIG. 3 is a left side view thereof where the right side view is a mirror image;

FIG. 4 is a top plan view thereof;

FIG. 5 is a bottom plan view thereof; and,

FIG. 6 is an exploded perspective view thereof with environment.

The broken lines in FIG. 6 are included for the purpose of showing environment and form no part of the claimed design.

1 Claim, 6 Drawing Sheets(56)
